No. 874,558.

PATENTED DEC. 24, 1907.

H. L. BEACH.

ALTERNATING DIRECT CURRENT SYSTEM OF CONTROL.

APPLICATION FILED MAR. 3, 1906.

UNITED STATES PATENT OFFICE.

HOWARD L. BEACH, OF WILKINSBURG, PENNSYLVANIA, ASSIGNOR TO WESTINGHOUSE ELECTRIC & MANUFACTURING COMPANY, A CORPORATION OF PENNSYLVANIA.

ALTERNATING-DIRECT-CURRENT SYSTEM OF CONTROL.

No. 874,558.

Specification of Letters Patent.

Patented Dec. 24, 1907.

Application filed March 3, 1906. Serial No. 304,096.

To all whom it may concern:

Be it known that I, HOWARD L. BEACH, a citizen of the United States, and a resident of Wilkinsburg, in the county of Allegheny and State of Pennsylvania, have invented a new and useful Improvement in Alternating-Direct-Current Systems of Control, of which the following is a specification.

My invention relates to systems of control for electrical and other devices and particularly to systems that embody two or more different supply conductors, from which currents of different kinds or degrees are derived by means of suitable collecting devices.

One object of my invention is to provide systems, having separate current collectors for the respective currents, with means for governing the operation of such collectors.

A further object of my invention is to provide means whereby the circuits of a system of the character specified may be adjusted automatically, according to the specific current collector in service; that is, in accordance with the character of energy supplied to the system.

Systems of distribution, from which both direct and alternating currents may be supplied to railway vehicles, are frequently provided with trolley conductors for the alternating current sections and third-rail conductors for the direct current sections. When the systems are so arranged, an overhead trolley conductor may also be provided for direct current sections where breaks occur in the third-rail, as, for instance, at road or railway crossings, and a special trolley collector may be employed to engage therewith.

It is the specific object of my invention to provide means whereby both the alternating and the direct current collectors may be prevented from occupying operative or service positions at the same time, and to further so organize the system that a change-over switch, whereby the control circuits may be arranged in accordance with the character of energy that is supplied thereto, may be automatically operated to correspond to the positions of the current collectors.

The single figure of the accompanying drawing illustrates, diagrammatically, a system embodying my invention.

Trolley collectors 1 and 2, here shown as of the pantograph type and especially con-

structed for the collection of high voltage currents, are adapted to engage a trolley conductor 3 and comprise, as important elements, springs 4 or other resilient means whereby the collectors are normally raised into engagement with the conductor 3, and pistons 5 and 6 that operate in cylinders 7 and between which fluid-pressure may be applied to effect lowering of the collectors.

Catches or hooks 8, that are adapted to engage corresponding eyes or other parts 9 of the trolleys, are normally retained in the positions shown by means of springs 10 and may be operated to catch or release the parts 9 by means of fluid-pressure exerted in cylinders 11 behind the pistons 12.

Direct current is normally supplied to the system through a shoe 13 that engages a third-rail 14, but at places where breaks occur in the third-rail, as for instance at highway crossings, a trolley collector 15 may be employed in connection with trolley conductor 16. The trolley conductor 16 spans the breaks in the third-rail, preferably at a lower elevation than the alternating current trolley conductor 3, and is provided with sloping approaches at its ends. The trolley 15 may also be of the pantograph type and its structural details may be similar to those of the trolleys 1 and 2, except that it will usually be smaller in dimensions because it is used only intermittently. It is normally maintained out of engagement with the conductor 16 by means of springs 17 and is raised into engagement therewith by means of fluid-pressure in a cylinder 18 between pistons 19 and 20.

The cylinders 7 and 18 communicate with a common supply pipe 21 to which fluid-pressure is admitted under the regulation of a valve 22 that is adapted to be operated by a magnet winding 23. Energy may be supplied to the magnet winding 23 from any suitable source, such as a battery 24, and its circuit is established by means of a change-over switch 25 that is adapted to occupy positions, indicated by broken lines D—C and A—C, for arranging the control circuits for direct and alternating current operation, respectively.

It will, of course, be understood that the change-over switch is adapted to arrange other circuits than those here indicated, in accordance with the character of the energy that is supplied to the system, it being usual

to interpose it either in the main motor circuits of an electrically-operated vehicle, or in the auxiliary or control circuits, for the purpose of changing the circuit relations of the motors or of the armatures and field magnet windings thereof according to the character of energy that is supplied to the system. Such a device is shown in a system that constitutes the subject-matter of another application, Serial No. 304,097, filed by me of even date herewith, but since the structural details thereof and the further arrangement of the circuits with reference thereto form no part of my present invention, I deem it unnecessary to further describe the same.

The change-over switch 25 is adapted to be operated by means of fluid-pressure-actuating devices 26 and 27, the supply of fluid to which may be governed by means of valves 28 and 29 that are controlled in their operation by means of magnet windings 30 and 31. A terminal of each of the magnet windings 30 and 31 is connected to the battery 24 and the remaining terminals are connected, respectively, to stationary contact terminals 32 and 33. The latter are adapted to be connected to other stationary contact terminals 34 and 35, respectively, by means of conducting segments 36 and 37 with which the movable member of the change-over switch is provided. The conducting segments 36 and 37 are so constructed and disposed that the circuit of the winding 30 will be interrupted when the change-over switch is in one of its extreme positions and the circuit of the winding 31 will be interrupted when the switch is in its other extreme position, and also so that the circuit of the winding which had not been previously energized to cause operation of the switch may become established by means of a relay switch 38, the upper and lower contact terminals 39 and 40 of which are connected, respectively, to contact terminals 34 and 35. The relay switch 38 is provided with an operating magnet winding 41 that is energized to effect operation of the switch to its uppermost position only when the shoe 13 engages the third-rail 14, or the trolley 15 engages the conductor 16.

The supply of fluid-pressure to the cylinders 11 and to the operating cylinders for the change-over switch 25 is controlled by means of a valve 42, having an operating magnet winding 43, the circuit of which is governed by means of a normally open switch 44. It follows that operation of the catches 8 is governed by the switch 44 and that the change-over switch 25 may not be operated, even though the valves 28 and 29 are open, unless the switch 44 is closed for the purpose of effecting the opening of the valve 42.

Under the conditions shown in the drawing, the circuits are arranged for alternating

current operation and if a properly equipped vehicle passes into a direct current section of the distributing system, so that the shoe 13 will engage the third-rail 14, the magnet winding 41 will be energized and the switch 38 will be moved to its uppermost position. A circuit will then be established from the battery through the switch 38 in its uppermost position, contact terminal 34, conducting segment 36, contact terminal 32 and magnet winding 30. The valve 28 opens to admit fluid to the device 26 and the change-over switch is moved to the position indicated by the broken lines D-C upon closure of the switch 44 and consequent opening of the valve 42. When the change-over switch is moved, a circuit will be established through the operating magnet winding 23 for the valve 22 and fluid-pressure will be supplied to the cylinders 7 and 18 and cause lowering of the trolleys 1 and 2 and raising of trolley 15. When the trolleys 1 and 2 have been moved to their lowermost positions the catches 8 will be operated automatically and the trolleys will thus be retained in these positions. The system may then be supplied with direct current from either the third-rail 14 or the trolley conductor 16 or from both of these devices and the vehicle may operate in the direct current section of the distributing system regardless of gaps in the third-rail.

The switch 44 being normally open and the valve 42 normally closed, the supply of fluid-pressure to the operating device for the change-over switch is prevented, regardless of whether or not the circuits of the magnet windings 30 and 31 are energized, so that if the shoe 13 becomes momentarily disengaged from the third-rail 14, as often occurs during operation, the change-over switch cannot be moved.

When the change-over switch occupies the position indicated by the broken lines D-C and a vehicle which is equipped in accordance with my invention, passes from a direct current section to an alternating current section of the system, the switch 38 moves to its lowermost position and the circuit of operating magnet winding 31 for the valve 29 is established. Then, by closing the switch 44, the valve 42 will be caused to open and admit fluid-pressure to the device 27 which operates the change-over switch to the position shown. The circuit of magnet winding 23 is thereby interrupted to permit closure of the valve 22 and reduction of the fluid-pressure within the cylinders 7 and 18 of the trolleys.

If the switch 44 is held closed or is closed again after the movement of the change-over switch, the valve 42 will open and fluid-pressure will be admitted to the cylinders 11 to operate the catches and release the trolleys 1 and 2 which are thereupon raised into en-

gagement with the trolley conductor 3 by means of the springs 4.

While my invention is shown and described as applied to a system in which both 5 alternating and direct currents are utilized, I desire it to be understood that it is not necessarily limited to such systems, inasmuch as it may be utilized in systems having a plurality of supply circuits carrying currents of 10 the same kind, either at the same or at different voltages.

I claim as my invention:

1. The combination with distributing conductors for direct and alternating current, 15 respectively; a collector device for direct current that is normally maintained out of engagement with the corresponding distributing conductor, and a collector device for alternating current that is normally maintained in engagement with the corresponding distributing conductor, of means for moving the collector devices into and out of engagement with the respective conductors, a change-over switch having positions corresponding to the different characters of energy, 20 and means actuated thereby for controlling the operating means for the collector devices.

2. The combination with distributing conductors for direct and alternating current, 30 respectively, a collector device for direct current that is normally maintained out of engagement with the corresponding distributing conductor, and a collector device for alternating current that is normally maintained in engagement with the corresponding distributing conductor, of means for moving the direct current collector device into engagement with its conductor, similar 35 means subjected to a like operating force for moving the alternating current collector device away from its conductor, a change-over switch having positions corresponding to the different characters of energy and 40 means, dependent in operation upon the position of one of the current collector devices, for governing the change-over switch.

3. The combination with distributing conductors for direct and alternating current, 50 respectively, a collector device for direct current that is normally maintained out of engagement with the corresponding distributing conductor, and a collector device for alternating current that is normally maintained in engagement with the corresponding distributing conductor, of means for simultaneously moving the direct current collector device into engagement and the alternating current collector device out of engagement 55 with their respective conductors, a change-over switch having positions corresponding to different characters of energy, 60

means, dependent in operation upon the position of the direct current collector devices, for governing the change-over switch, 65 and manually controlled means for further governing the operation of the change-over switch.

4. In an electric railway system having alternating current and direct current supply conductors for different sections, the combination with a collector for each kind of current, a change-over switch and pneumatic means for operating the same, of an automatic relay switch and a manually-operated switch for governing said operating means. 70

5. In an electric railway system having alternating current and direct current supply conductors for different sections, the combination with a collector for each kind of current, pneumatically-actuated means for controlling the operation of one or more of said collectors, a pneumatically-operated change-over switch, electro-magnetically controlled valves, an automatic relay switch 85 and a manually-operated switch for controlling the application of pneumatic pressure to said change-over switch. 80

6. In a railway system having alternating current and direct current supply conductors for different sections, the combination with separate collectors for the different kinds of current and means for operating said collectors inversely, of a change-over switch, means for operating said switch in accordance with the kind of current available and a manually-operated switch for opening and closing the governing circuit. 90

7. In an electric railway system having a plurality of supply conductors, the combination with current collectors for the respective supply conductors, of a change-over switch, pneumatic means for actuating the same, an automatic relay switch and a non-automatic switch for governing said actuating means. 100

8. In an electric railway system, the combination with alternating current supply conductors carrying different kinds of energy and separate collector devices thereof, of means for holding one of said devices in engagement and the other out of engagement with the supply conductor, means for oppositely actuating both of said devices, a change-over switch, an automatic relay and 110 a manually operated switch for governing said change-over switch. 115

In testimony whereof, I have hereunto subscribed my name this 28th day of February 1906.
